CHARLES ORME BASTIAN, OF LONDON, ENGLAND, ASSIGNOR TO COOPER HEWITT ELECTRIC COMPANY, OF HOBOKEN, NEW JERSEY, A CORPORATION OF NEW JERSEY.

ELECTRIC VAPOR APPARATUS.

1,110,608.

Specification of Letters Patent. Patented Sept. 15, 1914.

Original application filed January 27, 1913, Serial No. 744,306. Divided and this application filed December 5, 1913. Serial No. 804,819.

To all whom it may concern:

Be it known that I, CHARLES ORME BASTIAN, a subject of the King of Great Britain, and resident of London, England, 5 have invented certain new and useful Improvements in or Relating to Electric Vapor Apparatus, of which the following is a specification.

This invention has for its object improvements in or relating to vapor electric apparatus, especially lamps of the character known as vapor electric lamps. Such lamps are provided with a transparent tube containing electrodes, both of which are usually 10 of some volatilizable material, such as mercury. The luminous portion of the tube is commonly called the "burner" and this irrespective of whether the apparatus be used for giving light, or for any other purpose, 15 such as rectifying or rupturing electric circuits.

With all classes of mercury vapor lamps or other electric vapor apparatus it frequently happens that a small quantity of air 20 or other gas remains within the container or occluded in the mercury after the lamp has been sealed, and taken off the pump but according to this part of my present invention I form or arrange in any suitable 25 position on the lamp an enlargement or trap into which the air may be transferred by careful manipulation and retained there by solid mercury which latter may form one of the electrodes, and the air thus trapped is 30 thereby prevented from getting into the arc and disarranging the normal operation of the latter. If the said enlargement or trap be attached to the top of the anode (or 35 cathode) it serves the double purpose of a cushion for the mercury in such electrode 40 forcing the mercury back when the circuit is broken and preventing it from sticking in the tube.

Referring to the accompanying drawings:—Figure 1 shows a burner arranged approximately in a circular form with enlargement or bulb at each end of the circular container tube. Fig. 2 is a side elevation of Fig. 1, partly in section.

50 In Figs. 1 and 2 the small bore container tube *a* is shown arranged in a circular form or thereabouts with a positive electrode *e* and negative electrode *f* each of the same size or approximately so with enlargements

or bulbs *e* *f* located outside the path of 55 the arc stream. In this arrangement the mercury lies right around the tube *a* (before the lamp is started) so as to normally connect the electrodes *e* and *f* and advantageously a small bore tube is used with sufficient 60 mercury to normally fill said tube in order to connect the two electrodes *e* and *f*. When the burner is started by tilting same the mercury is separated at or about centrally between the two electrodes and is 65 caused to run back into each of the respective bulbs *e* *f* and the arc stream extends from or about the region of the electrode *e* around the circular tube to or near the electrode *f*. As the mercury diminishes at the 70 positive electrode *e* and accumulates at or near the electrode *f* the arrangement is such that similar action takes place as before described and the point of equilibrium is reached at which the respective levels of the 75 electrode surfaces remain constant or practically so throughout the operation of the burner.

On the container tube *a*—and at about midway between the electrodes *e* and *f*—I 80 arrange a small vertical tube *g* terminating in a bulb *g*¹ which is in closed connection with the interior of the said tube so that when the mercury is caused or allowed to pass around the container tube *a* to connect 85 the electrodes *e* and *f* as aforesaid part of said mercury will be forced up the tube *g* and form a small head of mercury which (when the burner is tilted to start the same) will cause the mercury to positively divide 90 at the point immediately below this said small column of mercury and thus insure starting the arc stream in the tube about centrally with respect to the electrodes and thus insures the positive starting up of the 95 burner in a regular manner. In the manufacture of these burners I find it advantageous to utilize this vertical column *g* and enlargement *g*¹ for the purpose of connecting to the vacuum pumps and the subsequent sealing off.

It will be obvious that if desired and where suitable the current may be passed in reverse direction through any of the burners illustrated. Therefore mercury 105 displaced from one electrode owing to the difference in heat potential between the electrodes can be replaced with mercury dis-

placed in the opposite direction owing to the difference in heat potential between the electrodes and by constructing the burner so as to utilize this discovery I am thereby enabled to establish and maintain constant quantities of electrode material at each electrode respectively without the passage of solid mercury through the arc path.

In the following claim the terms "burner" and "mercury" are (for the sake of brevity) respectively used to denote and include any suitable device and any suitable electrode material as hereinbefore defined or explained.

I claim as my invention:

15 In a burner for a vapor electric apparatus in which volatilizable electrodes are held

within a tube and in which, when the current is not flowing, there is a continuous column of mercury filling the tube between the electrodes, means for breaking the column at a predetermined point and for cushioning the volatilizable material, such means consisting of a chamber located above the tube and connected with the bore of the said tube.

Signed at London in the county of London England this 18th day of November A. D. 1913.

CHARLES ORME BASTIAN.
